STARTER GEARING

William L. McGrath, Elmira, N. Y., assignor to
Eclipse Machine Company, Elmira, N. Y., a
corporation of New York

Application March 3, 1934, Serial No. 713,891

7 Claims. (Cl. 74—8)

This invention relates to starter gearing for internal combustion engines of the type in which the driving connection is established automatically when the starting motor is energized and is disrupted when the engine becomes self-operative, and more particularly to an automatic starter gearing of the so-called side meshing type in which the meshing movement of the engaging gear member is transverse to its axis.

It is an object of the present invention to provide a starter gearing of the above type which is simple in construction and efficient and reliable in operation.

It is another object to provide such a device embodying special provisions to insure continuous cranking until the engine starts.

It is a further object to provide such a device in which the disengagement of the gearing may be arranged to take place at any desired speed of the driving gear.

It is another object to provide such a device in which engagement of the driving parts is prevented except when the starting motor is operated.

Further objects and advantages will be apparent to those skilled in this art from the following description taken in connection with the accompanying drawing in which:

Fig. 1 is an end elevation of a preferred embodiment of the present invention showing the parts in normal or idle position;

Fig. 2 is a similar view showing the parts in cranking position; and

Fig. 3 is a side elevation partly in section of the device as illustrated in Fig. 1.

Referring first to Fig. 3 of the drawing, there is illustrated a starting motor 1 having an extended armature shaft 2. A driving member in the form of a pinion 3 is freely journalled on a reduced portion 4 of the armature shaft and is yieldably connected for rotation therewith by suitable means such as a coil spring 5 anchored at one end as indicated at 6 to a driving head 7 fixed to the armature shaft, and anchored at its other end as indicated at 8 to a flange or driven head 9 on the pinion 3.

An intermediate transmission member in the form of a pinion 11 is arranged to mesh with the driving pinion 3 and to move bodily transverse to its axis into and out of driving engagement with a member 12 (Figs. 1 and 2) of the engine to be started. For this purpose a swinging bracket or cradle is provided comprising side members 13 and 14 journalled on extended smooth portions of the pinion 3, and carrying a

bearing member 15 forming a journal for the intermediate pinion 11. The journal member 15 may be retained in the bracket in any suitable manner as by means of a threaded connection such as indicated at 16.

Referring now more particularly to Figs. 1 and 2, it will be seen that according to the present invention there is provided a locking means for positively holding the intermediate pinion 11 in driving engagement with the engine member 12 during the cranking operation. As here illustrated this locking means is in the form of a toggle device comprising the toggle member 17 pivoted at 18 to a stationary part such as a bracket 19 mounted on the frame of the motor 1, and a second toggle member 21 pivoted at 22 to a toggle member 17 and pivoted at 23 to the journal member 15 on the swinging bracket 13, 14. Stop means in the form of shoulders 25 and 26 on the toggle members 17 and 21 respectively are provided to limit the pivotal movement about the pivot 22 to a straight line position as shown in Fig. 2, and yielding means in the form of a spring 27 is provided tending to straighten the toggle device.

Yielding means in the form of a spring 28 is provided for normally urging the bracket 13, 14 to its idle position so as to maintain the intermediate pinion 11 out of engagement with the engine member 12. It will be understood that the spring 28 is stronger than the spring 27 so that the spring 27 cannot straighten the toggle 17, 21, except when the spring 28 is overcome by the torque of the driving pinion 3 when the cranking operation is initiated.

Means are provided for releasing the locking device for the intermediate pinion 11 by breaking the toggle 17, 21 when the driving pinion 3 has attained a predetermined rotational speed corresponding approximately to the free spinning speed of the starting motor 1. As here shown this releasing or tripping means comprises a pair of centrifugal elements 29, 31 mounted on the armature shaft of the starting motor adjacent the driving pinion 3 with freedom for limited radial movement as indicated at 32 and 33 against the action of springs 34 and 35. The toggle member 21 is provided with an arm 36 carrying at its free end an adjustable abutment member 37 which is arranged adjacent the periphery of the centrifugal elements 29, 31 when the toggle is in its straight line position as illustrated in Fig. 2. It will be understood that the springs 34 and 35 are so calibrated, and the abutment member 37 is so adjusted that the centrifugal members 29,

31 will engage the abutment and break the toggle at the preselected speed of the starting motor at which it is desired to break the starting connection.

5 In the operation of this device and starting with the elements in the positions shown in Fig. 1, energization of the starting motor 1 causes rapid acceleration of the driving pinion 3 in the direction of the arrow *a*. The rotational inertia of 10 the intermediate pinion 11 causes the torque of the driving pinion 3 to swing the bracket 13, 14 until the intermediate pinion 11 engages the engine member 12. Further rotation of the driving pinion causes the intermediate pinion 11 to come 15 into full mesh with the engine gear, whereupon the spring 27 straightens the toggle 17, 21 thus locking the gearing in operative position as shown in Fig. 2, whereupon the cranking operation of the engine is initiated. During the cranking operation, the rotation of the armature shaft and 20 driving member 3 is insufficient to affect the centrifugal elements 29, 31 so that the gearing remains locked irrespective of variations in torque caused by passage of the engine over its compression points or even by feeble explosions or 25 false starts of the engine.

The continuous mechanical connection between the engine gear and the armature of the starting motor during the cranking operation has the 30 effect of increasing the moment of inertia of the engine flywheel by the moment of inertia of the armature multiplied by the mechanical advantage of the drive. Since the gear reduction of the drive may be in the order of twelve or fifteen 35 to one, it is obvious that this arrangement greatly increases the effectiveness of the flywheel in carrying on the rotation of the engine crankshaft after a feeble explosion. This is an important advantage at the present time when the reduction 40 in the size and weight of the engine flywheels has tended to aggravate the problem of false starting.

When the engine starts and becomes self-operative, the load is released from the starting 45 motor whereupon the motor shaft is rapidly accelerated by the torque of the motor and by the driving force of the engine gear. Centrifugal elements 29, 31 thereupon move out radially and engage the stop member 37 on the arm 36 of 50 toggle member 21 causing the arm 36 to be moved downwardly and to the right thus breaking the toggle and permitting the spring 28 to swing the bracket 13, 14 back to idle position with the assistance of the driving effect of the engine member 55 12 on the intermediate gear 11.

It will be readily appreciated that by the use of springs 34 and 35 of proper strength and by the adjustment of stop 37 the duration of the positive locked condition of the starter gearing 60 may be regulated in accordance with any desired conditions. Thus, in installations where false starts are prevalent the centrifugal device may if deemed desirable be so adjusted as to release only at a rotational speed of the motor which 65 is well above its free spinning speed, thus assuring continuous cranking until a true start is secured.

Although but one embodiment of the invention has been shown and described, it will be understood that other embodiments are possible and

various changes may be made in the details and arrangements of the parts without departing from the spirit of the invention as defined in the claims appended hereto.

What is claimed is:

1. In an engine starter drive a driving member, a transmission member bodily movable transverse to its axis to engage with a member of the engine to be started, means for holding the transmission member in engaging position and speed controlled means for releasing said holding means.

2. In an engine starter drive a driving member, a transmission member bodily movable transverse to its axis into engagement with a member of the engine to be started, means for biasing the transmission member toward idle position, means for locking the transmission member in engaging position and means operative at a predetermined speed of the transmission member for engaging and releasing said locking means.

3. In an engine starter drive a driving gear, a driven gear, an intermediate gear meshing with the driving gear and mounted for bodily movement transverse to its axis into and out of mesh with the driven gear, means for positively locking the intermediate gear in mesh with the driven gear and speed controlled means for releasing the locking means.

4. In an engine starter drive, a driving gear, a driven gear, an intermediate gear meshing with the driving gear and mounted for bodily movement transverse to its axis into and out of mesh with the driven gear, means including a toggle structure for positively locking the intermediate gear in mesh with the driven gear and means controlled by the speed of the driving gear for breaking said toggle to allow the intermediate gear to return to demeshed position.

5. In an engine starter a driving member, a transmission member bodily movable thereby into driving engagement with a member of the engine to be started, means including a toggle structure for holding the transmission member in engaging position and means including a centrifugal device responsive to the speed of the driving member for breaking said toggle.

6. In an engine starter, a driving member, a transmission member bodily movable thereby transverse to its axis into driving engagement with a member of the engine to be started, means including a toggle structure for holding the transmission member in engaging position, means normally maintaining the transmission member in idle position, yielding means tending to straighten the toggle when the transmission member is moved to driving position and means for breaking said toggle at a predetermined speed of the driving member.

7. In an engine starter, a driving member, a transmission member bodily movable thereby transverse to its axis into driving engagement with a member of the engine to be started, means including a toggle structure for holding the transmission member in engaging position, means including a centrifugal device mounted to rotate with the driving member and operative at a predetermined speed to break said toggle, and yielding means thereupon operative to move the transmission member to idle position.
